UNITED STATES PATENT OFFICE.

CLARENCE J. BROWN AND CLAUDE E. BROWN, OF CHICAGO, ILLINOIS, ASSIGNEES, BY MESNE ASSIGNMENTS, TO BROWN PAPER GOODS COMPANY, OF CHICAGO, ILLINOIS, A CORPORATION OF ILLINOIS.

MACHINE FOR FORMING PAPER RECEPTACLES.

1,419,355.

Specification of Letters Patent. Patented June 13, 1922.

Application filed July 5, 1918. Serial No. 243,331.

To all whom it may concern:

Be it known that we, CLARENCE J. BROWN and CLAUDE F. BROWN, citizens of the United States, and residents of Chicago, county of Cook, and State of Illinois, have invented new and useful Improvements in Machines for Forming Paper Receptacles, of which the following is a specification, the principle of the invention being herein explained and the best mode in which we have contemplated applying that principle, so as to distinguish it from other inventions.

Our invention relates to machines for forming paper receptacles and particularly to machines adapted to glue, string and form or fold up into proper shape prepared blanks intended for oyster pails, ice cream buckets, etc. More particularly our said improved machine relates to automatic mechanism of this character which shall be economically built and assembled in the first instance, which is designed to function without easily being injured or getting out of adjustment, which shall be thorough in its operation, and which shall have a capacity for a very large production in any given time.

The annexed drawings and the following description set forth in detail certain means embodying our invention, the disclosed means, however, constituting but one of various mechanical forms in which the principles of the invention may be applied.

In said annexed drawings:

Figure 1 represents a front elevation of our improved machine, a completed pail having just been ejected from the bottom thereof and another blank being shown in dotted lines approximately midway the top and bottom of the machine; Figure 2 represents an elevation of the left side of the machine; Figure 3 represents a vertical section taken through the center of the machine and looking toward the right side thereof; Figure 4 is a plan view, taken in the plane indicated by the line IV—IV, Figure 1, of a part of the top of the machine, illustrating the pulling from a magazine by suction of a blank about to be started through the machine by certain feeding rolls plainly shown, said view being upon a scale approximately three times as large as that used in the preceding figures; Figure 5 represents a transverse section of a fragmentary part of the machine and taken in the plane indicated by the line V—V, Figure 4; Figure 6 represents, upon the same scale as that used in Figure 4, a vertical longitudinal section of upper parts of the machine, said view looking toward the right of the machine and being taken in a plane somewhat beyond the center line, certain disappearing fingers and the cam operating them, hereinafter fully described, being omitted so that certain shear cams can be clearly shown; Figures 7 and 8 represent, upon said enlarged scale, fragmentary vertical sections of said disappearing fingers and the cam for actuating them and of said shears and their actuating cams, the parts shown in Figure 8 being similar to certain parts shown in Figure 6 but in the relative positions where the shears have just been closed and have cut the tape, hereinafter more fully described, the planes in which said figures are taken being indicated by the lines VII—VII and VIII—VIII, respectively, Figure 10; Figure 9 is a front elevation of the upper part of the machine, upon said enlarged scale, showing, however, only the lower part of the structures shown in Figure 6; Figure 10 represents, upon said enlarged scale, a plan section taken from the two planes designated by the lines X—X, Figure 6, of a threading device, hereinafter more fully described, this view showing the position just after certain grippers have taken hold of the tape, the view also showing the cams and connected parts for operating the shears and disappearing fingers; Figure 11 represents a similar view of the threading device when the grippers are pulling the tape back around certain stop pins hereinafter more fully described; Figures 12, 13, 14 and 15 show how the gripper jaws are opened to grasp the tape and how they move back without opening, Figure 12 being a plan view as the vertical part of the jaw is just striking against a latch hereinafter more fully described, Figure 13 showing the jaw partly opened by the latch, said jaw remaining open until the front of the gripper passes by the plane of the tape and both above and below the latter, Figure 14 showing the relative positions when the vertical part of the jaw has just slipped off the latch and the spring has closed the grippers on the tape, and Figure 15 showing the relative positions

when the grippers are moving back with the tape, the pivoted latch having swung back and allowed the grippers to pass without being opened; Figure 16 represents a view 5 of the threading device similar to Figures 10 and 11, this view showing the position just after the vertical part of the gripper jaw has been pushed back by certain releasing fingers and the tape has been released; 10 Figure 17 represents an elevation of the gripper jaw, taken from the plane indicated by the line XVII—XVII, Figure 19, the dotted line position showing how the upper gripper jaw is opened by the pivoted latch 15 mentioned in Figures 12 to 15; Figure 18 represents an elevation of the gripper jaw, taken from the plane indicated by the line XVIII—XVIII, Figure 17; Figure 19 represents a plan view of the gripper jaw and 20 its bracket, said Figures 17, 18 and 19 being upon a scale twice the size of that used in Figure 16; Figures 20, 21, 22 and 23 represent motion studies of a tape measuring device, showing four different positions of a 25 pulling device, the details of which will be hereinafter more fully given, Figure 20 representing the pulling device at its extreme right position, after it has taken hold of the tape and is just starting to pull the same 30 across the front of the machine, Figure 21 showing the pulling device crossing the front of the machine with the tape, moving toward the left, Figure 22 showing the pulling device at its extreme left position with 35 the tape, and Figure 23 representing the pulling device moving to the right to secure more tape, all of said views being upon the enlarged scale used in Figure 16; Figure 24 represents an elevation of fragmentary portions 40 taken from the plane indicated by the line XXIV—XXIV, Figure 23; Figure 25 represents a plan view of the elements shown in Figure 24; Figure 26 represents a longitudinal section taken in the plane indicated by 45 the line XXVI—XXVI, Figure 23; Figure 27 represents certain parts shown in Figure 26, upon an enlarged scale; Figure 28 represents a longitudinal section taken in the plane indicated by the line XXVIII—XXVIII, 50 Figure 21; Figure 29 represents a transverse section taken in the plane indicated by the line XXIX—XXIX, Figure 21; Figure 30 represents a transverse section taken in the plane indicated by the line XXX—XXX, 55 Figure 21; Figures 31 and 32 represent horizontal sections of the two jaws of a tape guiding device, one of said jaws being pivoted and two different positions thereof being shown; Figure 33 represents, upon a 60 scale one and one-half times the size used in Figure 1, a plan section of the lower part of the machine looking from the rear toward the front, certain projecting mechanism, hereinafter more fully described, for pushing 65 the formed pail out of the machine,

being shown in its extreme forward position; Figure 34 represents, upon the scale used in Figure 33, a vertical section of the lower part of the machine looking toward the left of the machine and showing particularly the projecting mechanism in its extreme forward position, as also shown in Figure 33; Figure 35 represents a part of the mechanism shown in Figure 34 but illustrating the relative positions when the projecting mechanism is returning toward the rear and a stripper, hereinafter more fully described, is being released so that it can slide back under the action of a certain spring; Figure 36 represents the mechanism 70 shown in Figure 34 when the projecting mechanism has reached its extreme rear position; Figure 37 represents the same when the projecting mechanism has moved part way forward and certain upper folding fingers, hereinafter more fully described, are in their lower position; Figure 38 represents, upon the same scale, a front elevation of the lower part of the machine, showing certain lower side folding fingers in their upper 75 position and certain side pressure plates in their inner position; Figure 39 represents a detail view of a certain front pressure roller, hereinafter more fully described; Figure 40 represents a transverse section or fragmentary parts, taken in the plane indicated by the line XL—XL, Figure 34; Figures 41 and 42 represent transverse sections taken in the planes indicated by the lines XLI—XLI and XLII—XLII, Figure 34; Figures 43 and 44 represent front elevations of the lower part of the machine, upon the same scale, showing for the most part the operation of certain folding mechanism, Figure 43 showing upper side folding fingers in 80 their lower position and Figure 44 showing bottom end folding fingers in their inner position; Figures 45 and 46 represent, respectively, a blank designed to be formed up into a completed pail as it appears when 85 being fed to the machine and as it appears after it has been supplied with a bail tape during its passage through the machine; Figures 47, 48, 49 and 50 are operation studies of the blank showing the sequence of the 90 folds as the blank is being formed into a completed bucket, Figure 47 being a perspective of the blank as formed by the action of the projecting mechanism, Figure 48 showing the blank after the first fold has 95 been made, this fold being a downward folding of the upper side portions of the blank, Figure 49 showing the blank after the second fold has taken place, this fold being the inner folding of bottom end portions of the 100 blank, and Figure 50 showing the blank after the third and last fold has taken place, this fold being an upper folding of lower side portions of the blank, which portions have, during the transit of the blank through 105

110

115

120

125

130

the machine, received the glue and have also had securely impressed upon them and in the glue the ends of the tape bail, as will be hereinafter fully explained; Figure 51 represents the complete container as it appears when filled and closed.

By our improved machine it is designed automatically to feed therethrough successively a plurality of blanks cut so as to form, when bent up along predetermined lines, an ice cream, oyster or similar container. The machine automatically effects such bending operations and also automatically applies glue to predetermined portions of the blank and strings the blank at predetermined points with lengths of tape which are also securely fastened to the blanks, such lengths of tape being automatically furnished by the machine at the proper times and places and forming the bails of the completed pails, the blanks being provided in the first instance, and before being manually fed to the magazine, with certain cuts into which the said ends of tape are inserted. As plainly shown in Figure 1, wherein one completed pail is just being ejected from the machine and another blank is approximately midway through the machine, having had glued thereto the tape length, the machine is adapted to function so as to bring its several parts into positions just short of operating upon three blanks at one time, the relative positions of the upper parts of the machine, shown in Figure 1, being those when a blank is about to be conveyed from the magazine to the upper positive feeding members.

The above functions are performed by a number of generally segregated groups of elements assembled and supported in a suitable frame, such groups being as follows:

(1) Means for periodically pulling a blank 261 by suitable suction mechanism from a group of blanks disposed generally vertically in a magazine at the upper front part of the machine, related mechanism at the same time causing the blank to drop a little where it can be caught and positively conveyed in a vertical position down the front of the machine. These means are in general grouped around a suction device indicated by the ordinal 10, Figures 2 and 4.

(2) Means for seizing and positively feeding the blank so extracted from the magazine and aligned for its passage down the front of the machine. These means are in general grouped around shafts 15 and 16, Figures 1, 2, 3, 4 and 6.

(3) Means, including further blank-feeding means, providing a backing for the blanks, this backing, of course, being upon the front part of the machine, against which backing the blanks are pressed when glue is applied by certain devices at predetermined places on the blank. These means are in general grouped around a roller 32, guide

member 60 and daubers 23, Figures 1, 3, 4, 6 and 9.

(4) Means conveying into the machine a certain length of tape and gripping this length of tape at each end thereof, such length of tape being adapted to form the bail of the completed pail. These means are grouped around cam 49 on shaft 280, Figures 1, 33, 38, 43 and 44; arms 72 and 73, and rods 68, Figures 1, 6, 7, 8, 9, 10 and 23; 75 jaws 66 and 67, Figures 1, 9 and 20-23; and jaws 300 and 301, Figures 10-19.

(5) Means for severing this length of tape from the spool of tape from which it has been derived. These means are grouped 80 around cams 290 and 291 on shaft 33, and a pair of shears 285 and 286, Figures 1, 2, 3, 6, 8, 9 and 10.

(6) Means providing a station for this length of tape in a plane where it will intercept the descending blank. These means are grouped around a cam 288 upon shaft 33, an arm 80 and a pair of vertically reciprocable pins 78, Figures 1, 3, 7, 9, 10, 11 and 16. 90

(7) Means transferring the severed length of tape rearward to this station, i. e., from position in which the tape 63 is disposed to the position defined by the pins 78, Figure 7, where the length of tape will intercept 95 and be carried down by the descending blank. These means are grouped around a pair of cams 61 on shaft 62, Figures 1, 3, 6, 9 and 10, and the aforesaid jaws 300 and 301. 100

(8) Means adapted to release the length of tape from the aforesaid jaws 300 and 301 as or immediately prior to the time the tape intercepts the descending blank. These means are grouped around a pair of cams 105 57 upon the shaft 22 and a pair of trip fingers 295 and 296, Figures 1, 3, 6, 10, 11 and 16.

(9) Means adapted to seal the ends of the severed tape length against and in the 110 glued parts 270 of the blank. These means are grouped around a pair of rolls 40 mounted upon shaft 168 and a backing bar 39, Figures 3, 6, 7, 10, 11 and 16.

(10) Means adapted to continue the positive feeding of the blank down the front part of the machine. These means are grouped around a pair of rolls 220 and 221 mounted upon the shafts 222 and 223, Figures 1, 2, 3, 6 and 9. 115

(11) Means providing a mandrel about which the blank may be bent and formed up into a box or receptacle shape and reciprocating this mandrel into and out of the path of the descending blank, the mandrel 125 alone by its movement partway in one direction bending the blank back upon itself from both sides of a central part 268 which becomes the bottom of the completed box, as shown in Figure 47, these means being so 130

constructed as to provide a "dwell" during which the box is further and completely formed around the mandrel. These means are grouped around a mandrel 83, a cam 85 upon a shaft 282, and stop plates 176 and 177, Figures 1, 2, 3, 33, 34, 35, 36 and 37.

(12) Means for turning down the upper parts 265 of the short sides of the blank 261 about the mandrel, as shown in Figure 48. 10 These means are grouped around a cam 51 upon the shaft 281, a bar 91 and a pair of fingers 90, Figures 1, 33, 38, 43 and 44.

(13) Means adapted to turn in the end flaps 266 of the bottom against the sides 265 of the blank, as seen in Figure 49. These means are grouped around a cam 95 upon the shaft 281, a bar 99 and a pair of fingers 98, Figures 1, 33, 34, 36, 37, 38 and 44.

(14) Means for turning up the lower 20 glued parts 262 of the sides of the blank, as seen in Figure 50. These means are grouped about a cam 111 upon the shaft 280, a bar 107, and a pair of fingers 106, Figures 1, 3, 33, 34, 36, 37, 38, 43 and 44.

(15) Means for squeezing and holding 25 the parts 262, 265 and 266 of the blank against the mandrel to complete the forming and sealing of the blank while the mandrel is finishing its movement in one direction.

30 These means are grouped around a pair of cams 114 upon the shaft 282, a pair of bars 116 and a pair of squeeze plates 118, Figures 1, 33, 34, 35, 36, 37 and 38.

(16) Means adapted to strip the completed blank from the mandrel and free the same from the machine while the mandrel is moving in the other direction. These means are grouped around a pivoted dog 133 and a pin 131 provided at one end with 40 a plate 130 and at the other end with a pointed upturned member 134 over which said dog is adapted to drop, Figures 3, 33-37, 43 and 44.

45 For supporting and operating the above-mentioned mechanisms we have provided a supporting frame within which are carried by suitable brackets a shaft 1 disposed transversely of the machine and at the upper central part thereof. Upon the right hand end of this shaft is mounted a hand wheel 2, as plainly shown in Figure 1, utilized for adjustment of the primary feeding means so that the first blank may be fed from the magazine at the proper moment relative to 50 the several positions of the different parts of the machine. Upon this shaft 1 is also mounted a cam 54 utilized in connection with the positive pulling of the blank from its lowered position in the magazine, as will be hereinafter fully explained. Disposed in about the same horizontal plane as the shaft 1 is a rear shaft 6, Figures 2 and 3, utilized in connection with the operation of the suction means 10 which are adapted successively 55 to extract the blanks from the magazine.

Forwardly of the shaft 1 are the shafts 15 and 16 upon which are mounted rollers 18 and 17, respectively, Figures 1, 3, 4 and 6, utilized in connection with the primary positive feeding of the blank. 70

In a plane below the aforementioned shafts are a series of shafts whose general purposes will now be described. The forward shaft 33 carries the cam 288 approximately midway of its ends utilized in connection with the operation of the vertically reciprocable fingers 78 and the cams 290 and 291 utilized in connection with the operation of the shears 285 and 286. To the rear of shaft 33 is a shaft 31 provided with the 75 roller 32, Figures 1, 3, 6 and 9, adapted in connection with the guide segment 60 secured to shaft 22 immediately to the rear, to provide a secondary positive feeding means for the blank. Upon said shaft 22 are also mounted the pair of daubers 23 utilized in applying glue upon certain predetermined portions of the blank. Also carried upon said shaft 22 is a pair of cams 57 utilized in connection with the operation of the pivoted trip or releasing fingers 295 and 296, Figures 6 and 16. Rearwardly of 80 said shaft 22 are two shafts 25 and 27, Figures 2 and 3, utilized in connection with the applying of glue to the aforesaid daubers 23. 85

90 Disposed below the shafts just described and forwardly of the machine is a shaft 168 carrying the pair of rollers 40 adapted in connection with the blacking bar 39 to seal the ends 63' of the severed length of tape 100 in the glue 270 and against the inner surface of the lower side folds 262 of the blank 261.

Below said shaft 168 are the pair of shafts 222 and 223 carrying the pair of rollers 220 and 221 adapted to provide a further positive feeding means for the descending blank. Rearwardly of the shaft 223 is the shaft 62 upon which are mounted the pair of cams 61 utilized in connection with the pivotal movement of the clamping jaws 300 and 301 into 105 and out of the path of the descending blank for the purpose of bringing the severed length of tape to the plane of said path.

110 Disposed in the lower rear part of the machine is the shaft 282, Figure 33, carrying near its ends a pair of bevel gears 283 and 284 which severally mesh with a second pair of bevel gears 292 and 293 carried upon shafts 280 and 281, respectively, which are disposed longitudinally of the machine and upon the right and left sides thereof, respectively. Also mounted upon said shaft 282 are the pair of cams 114 utilized in connection with the operation of the squeeze plates 118; and the cam 85 utilized in connection 115 with the reciprocal movements of the mandrel 83. Also carried upon one end of said shaft 282 is a pulley 287 for receiving driving power from any suitable source. Upon the forward end of the shaft 281 is provided 120

125

130

the cam 95 utilized in connection with the operation of the pair of fingers 98 serving to turn up the bottom ends 260 of the blank, as seen in Figure 49. Also mounted upon said 5 shaft 281 is the cam 51 utilized in connection with the operation of the pair of fingers 90 adapted to turn down the upper sides 265 of the blank, as seen in Figure 48. Mounted upon the forward end of the shaft 280 is the 10 cam 49 utilized in connection with the operation of the device furnishing lengths of tape for bails and also the cam 111 utilized in connection with the operation of the pair of fingers 106 adapted to turn up the lower 15 glued sides 262 of the blank 261, as seen in Figure 50.

The gearing mechanism utilized to interconnect the several shafts and related elements hereinbefore described consists of a 20 gear 44 mounted upon shaft 282, Figures 2 and 33, and meshing with an idler 42 upon a shaft 279, in turn meshing with a gear 35 upon the shaft 62 which meshes with a pinion 37 upon the shaft 222. Through an 25 idler pinion 34 carried upon a shaft 278 movement is communicated to the shaft 22 by means of a gear 21, said gear intermeshing with forward and rearward pinions 30 and 24, mounted upon shafts 31 and 25, respectively, 30 by means of which rotation is given to shafts 33 and 27, respectively, through gears 277 and 38. Said gear 21 also intermeshes with a gear 4 mounted upon the shaft 1, which gear 4 meshes with a gear 5 and pinion 20 mounted upon shafts 6 and 16 respectively. Rotation is communicated to shaft 15 by means of a pinion 3 meshing with said pinion 20. This shaft 15 is not secured in fixed brackets but is mounted in a 35 pair of rock arms 26, Figures 1, 3 and 4 provided with central hubs 29 loosely mounted upon the shaft 16. The other ends of said rock arms 26 are connected by a bar 19. The reason for this construction will be herein- 40 after fully explained.

The main members of the supporting frame are indicated by the right and left hand side members 135 and 136, respectively, consisting of continuous members comprising two 45 corner uprights and upper cross pieces 137 and 138, respectively. Said members 135 and 136 are connected and braced by the front transversely disposed frame members 139, 140 and 141, Figure 1; by the central 50 transversely disposed frame member 182, Figure 33; by the rear transversely disposed frame members 183 and 184, Figure 2; by the right-hand side frame member 185; and by the left-hand side frame member 186, said 55 auxiliary frame members also supporting various mechanisms, as hereinafter fully explained. Carried upon the upper part of this frame is an auxiliary frame designed to provide a magazine for holding a large number 60 of pail blanks, as indicated in Figures 1, 2 and 3, from which they are periodically extracted by the suction mechanism herein- 65 after fully described. This auxiliary frame comprises the upwardly extending right and left side angles 142 and 143, respectively, combined and connected with the side frame comprising the right and left side members 144 and 145 and connected by rear member 146. Mounted in the forwardly projecting members 144 and 145 is a shaft 13 upon 70 which is mounted an anti-friction feed roller 14 against which the blanks 261 lean at their upper ends, as plainly shown in said Figure 3. The primary supports for the blanks 261 in the magazine are furnished by the forwardly extending frame members 147, Figures 3 and 4, supported by braces 148 and 149 mounted upon the auxiliary frame members 142 and 143 and adjustably connected to the said frame members 147 by rods 150 thread- 75 connected to said braces 148 and 149 at one end and secured at the other end to said members 147. The blanks 261 are of the design plainly shown in Figure 45 and rest by the edges in which the cuts 263 are made 80 upon the frame members 147, the lower flaps 267 of said blanks depending through and below said members 147, as plainly shown in Figure 3. The lower end of said members 147 are provided with slight shoulders 151 85 against which the lower edges of the sides 262 of the blanks rest and over which they must be pulled when they are extracted from the magazine. Also, the top of the guide- 90 way portions of the members 147 are provided with sharp outer edges 152, as plainly shown in Fig. 5. Also carried upon the auxiliary frame members 142 and 143, is a rearwardly extending U-shaped member 153 shown in Figures 3 and 4, running trans- 95 versely of the machine and across the same, as plainly shown in said Figure 4, for a purpose hereinafter fully described.

After the machine has been adjusted through the medium of the hand wheel 2, 110 the blanks are periodically extracted from the magazine through the medium of suction mechanism now to be described. It will be noted in Figure 4 that the suction pipe 10 is forked at its forward end so as to provide 115 a pair of suction mouths 11 bearing up against both sides of the forward blank 261. The rear of said suction pipe 10 is coupled to a section of rubber tube 9, Figure 2, intersecting a check valve 58 which is connected to a pump 52 connected to a second 120 check valve 59. Said pump 52 is supported upon a bracket 159 supported upon the rear transverse frame member 183, Figure 3. The connecting rod 53 of said pump is connected to an eccentric 53' mounted upon the shaft 6. Carried upon said shaft 6 is a cam 7 adapted to rock a lever 8 pivotally mounted upon the frame members 135 and 136 and co-operating for this purpose with 125 130

a roller 41 mounted upon said lever 8, the upper free end of said lever supporting a coupling member 43 connected to and enveloping and supporting the ends of the 5 section 12 of the suction pipe 10 and the rubber tubing section 9. Carried beneath the forward yoke members of the suction tube 10 are members 45 provided with a cam surface 46 adapted to ride upon the 10 transversely extending portion of the member 153. It is evident from the foregoing description that the rotation of the shaft 6 and the consequent actuation of the pump 52 will result in the periodic pulling by suction 15 of the forward blank 261 from the magazine over and by the shoulders 151 of the members 147 and, due to the cam surfaces 46 of the members 45, the slight lowering of said withdrawn blank within the 20 machine. The mechanism is designed to tend to keep the suction mouths 11 always up against the forward blank, due to the provision of a spring 154, Figures 2, 3, 4 and 6, connected at one end to the transverse 25 portion of said member 153 and at the other end to a coupling member 47 enveloping the ends of the suction pipe 10 proper and the element 12 thereof. The check valve 59 is adapted to be closed to the atmosphere 30 when the connecting rod 53 makes its forward stroke, thereby creating suction within the pump 52, and to be opened when the crank arm makes its rearward stroke. The check valve 58 is never open to the atmosphere 35 and is closed to the pump 52 when the crank arm 53 makes its rearward stroke and open to said pump when the crank arm makes its forward stroke.

When a blank has been extracted from 40 the magazine and positioned in a slightly lowered position in the machine, as hereinbefore described, the means now to be described function for positively feeding the blank down the front of the machine. As 45 hereinbefore generally mentioned, these means center around shafts 15 and 16 and connected parts, Figures 3 and 6. Mounted upon said shafts 15 and 16 are the rollers 18 and 17, respectively, between which and 50 by the frictional contact of which the blank will be fed downwardly. In order that these rollers may be brought into positive contact with the blank, the shaft 15 is capable of a limited reciprocatory movement 55 in the arc of a circle, of which the shaft 16 is the center, by the mechanism now to be described. It will be noted from an inspection of Figures 1, 3, 4 and 6, that there is mounted upon the shaft 1 the cam 54 upon 60 which a roller 55 is adapted to ride, said roller 55 being carried upon one end of an arm 56, the other end of said arm being connected to the bar 19 which is secured at its two ends, respectively, in the ends of the 65 two rock arms 26, provided with the hub

portions 29 rotatably mounted upon the shaft 16, said rock arms 26 providing bearings at their other ends for the shaft 15. It is evident, the mechanism being properly timed, that the rocking of the arms 26, due to the cam action between the parts 54 and 55, will bring the roller 18 up above the bottom edge of the blank 261 so that the frictional engagement between the rollers 17 and 18 and said blank therebetween will result in the positive downward feeding of the blank.

The means next to be described consists in a backing member against which the blank may be pressed by certain daubers 80 also to be described whereby glue may be applied to certain portions of the blank by said daubers. As hereinbefore mentioned briefly, these means are centered around a roller 32 and daubers 23, Figures 1, 3, 4, 6 85 and 9. This roller 32 is mounted upon shaft 31 all so proportioned that the plane intersected by the extreme rear edge of the roller 32 is the plane down which the descending blank is fed, said roller 32 providing the 90 backing hereinbefore mentioned and against which the blank 261 is pressed when the glue is applied. Mounted upon the shaft 22 by means of hub portions 23 are the daubers 23 connected to said hub portions by arm 95 23². The gluing operation is then very apparent from an inspection of Figures 3 and 9. It will be noted that the daubers intersect the blank some considerable distance upon either side of the central longitudinal plane thereof, it being designed to apply the glue to those portions of the blank indicated by the ordinal 270, Figures 45, 46, 47 and 48. In order that the blank may be positively kept against the backing roller 105 32, a segment of a roller, forming the guide member 60, is provided, as plainly shown in said Figures 3 and 9. The glue is applied to the dauber members 23 from a roller 48, Figure 3, mounted upon the shaft 25, said 110 roller in turn receiving the glue from a roller 50 mounted upon the shaft 27, which roller 50 intersects the interior of a chamber 119 provided with glue 120, a scraper 121 being provided, as shown.

The machine is designed in the meantime to have brought into the body thereof adjacently to the path of the descending blank, but somewhat forwardly of said path, tape from a suitable spool thereof, such a length 120 of such tape having been brought into this position as will, when severed from the body of the tape and applied to the blank by the means hereinafter described, serve as a bail for the completed bucket. As hereinbefore mentioned briefly, these means now to be described in detail center around the cam 49 provided upon one of the lowermost shafts, viz, right hand shaft 280, an arm 73, a pair of rods 68, a pair of jaws 66 and 67 125 130

and a pair of jaws 300 and 301, Figures 1, 20, 21, 22 and 23. The spool of tape is designated by the ordinal 64 mounted upon a pin 162 secured at its ends in the arms 129 of a yoke-shaped bracket 128 secured to frame member 135, all as plainly shown in Figures 1, 2 and 3, the tape itself being indicated by the ordinal 63. The tape 63 is fed up the right front part of the machine 5 over an anti-friction roller 65. It is necessary at the beginning of the operation of the machine manually to thread the tape between two guide members 233 and 234 provided with intersecting recesses 233' and 234', respectively, Figures 25, 31 and 32, of which the guide member 233 is stationary and formed up from a bracket member 235 secured to a bracket 236 supported by frame members 135, and the guide member 234 is 10 pivoted upon a pin 237 mounted in ears 238 formed up from the guide member 233, as plainly shown in Figures 24 and 25, 31 and 32. These members 233 and 234 are in reality guide members, not being adapted to bind the tape or resist the movement of the same therethrough further than, when in the position shown in Figure 31, to prevent the same slipping out by its own weight. Referring to Figure 1, it will be noted that 15 the aforesaid cam 49 co-operates with a roller 75 secured to the arm 73 to rock said arm about a pivotal point 76 at which one end of said arm is secured to the frame member 135, a torsion spring 74 being provided tending always to hold said arm 73 in the position shown in said Figure 1. Pivotedly connected to the upper and other end of said arm 73 is the arm 72 plainly shown in Figures 20, 21, 22 and 23, disposed 20 transversely of the front of the machine and having pivoted to it at its left-hand end a downwardly extending arm 71 formed with the lower jaw member 67 and pivoted intermediate of jaw 67 and its pivotal connection with arm 72 to a second downwardly extending arm 70 formed with the upper and second jaw member 66 adapted to co-operate with jaw member 67. The support for said downwardly extending arm 70 is furnished 25 by a block 69 provided with recesses 69' therethrough and longitudinally thereof, by means of which said block 69 is adapted to slide upon rods 68 and be supported, said rods 68 in turn being supported at their ends 30 by rearwardly extending members 77 secured to the brackets 125. It is evident from an inspection of Figures 20, 21, 22 and 23 and the foregoing description that, when the arm 72 is in its extreme right-hand position, 35 as plainly shown in Figures 1 and 20, the noses of the jaw members 66 and 67 will have entered the intersecting recesses 233' and 234' provided in the guide members 233 and 234 and will be in their closed position, 40 having gripped the extending end of the tape 63 disposed in said recesses where it has been initially threaded by hand, as hereinbefore mentioned. It is also evident that a proper timing of the mechanism will at the required times and periodically furnish a length of tape 63 forwardly of the machine and in the position illustrated in Figure 22. It is now necessary to grip said length of tape before the same is released by the jaws 66 and 67 and to sever the same from 45 the body of tape proper. This is effected by mechanism centering around the pairs of jaws 300 and 301, plainly shown in Figures 10 to 19 inclusive. As plainly shown in Figures 17, 18 and 19, said jaws comprise body portions 303, vertically extending portions 307 and horizontally extending portions 302 forming an upper jaw adapted to co-operate with a second horizontally extending portion 304 forming the lower jaw. 50 Ears 309 are formed up from the body portion 303 and provide a support for a pin 305 upon which is mounted a spring 308 so disposed as to bear against the vertically extending portion 307 of the upper jaw and 55 hold the jaws normally closed. The body portions 303 of these jaws 300 and 301 are adjustably secured at one end to brackets 181 pivotally mounted upon frame members 166 which are supported upon the frame members 135 and 136. Said brackets 181 are formed with bearing surfaces for loose pins 187 upon which are mounted universal joint members having a pair of ears 188 forming bearings for a pivot pin 189 upon which 60 is pivotally mounted an arm 117, hereinafter more fully described. It is evident that three pivotal axes are thus provided in connection with the swinging of the jaws 300 and 301 into and out of the path of the 65 descending blank, the two pivotal axes centered around the pins 187 and 189 providing in effect a universal joint. This pivotal movement of the jaws 300 and 301 into and out of the path of the descending blank is 70 effected by the pair of cams 61 secured to the shaft 62 with which a pair of rollers 102 are adapted to co-operate, said rollers being mounted upon arms 103 pivoted at 104 to brackets 166 secured to frame members 135 and 136. Pivoted upon the pin 189 secured in the ears 188 of the bracket 181 is an arm 117 provided with a forked end 190 which is connected to arm 103 by an eye screw 191. A spring 192 tends to hold arm 117 normally 75 in the position shown in Figure 11. It is evident that this construction will provide for the periodic swinging into and out of the path of the length of tape, shown in Figures 20, 21, 22 and 23, of the jaws 300 and 301. Normally these jaws are in their closed position. In order that the jaws may be opened to receive the tape, the means now to be described are provided. The upper 80 jaw 302 of each of the members 300 and 301 85

is provided with the upwardly extending portion 307 which is adapted, as the jaw is moved toward the tape 63, Figure 12, to strike against a latch or trip 251, mounted 5 upon pivot point 252, said pin being supported in the arms 253, Figure 11, recesses 254 in said arms 253 being provided within which said latches 251 are disposed. Said arms 253 are supported upon brackets 255 10 secured to brackets 236 mounted on frame members 135 and 136. This mechanism swings the jaws 302 back into the position shown in Figures 13 and 17, the jaws thus being opened and remaining open until the 15 front of the grippers are disposed above and below the tape in the position shown in Figures 10 and 14. A further forward pivotal movement of the jaws 300 and 301 will result in the slipping off from the latch 251 of the vertical part 307 of said jaws and the closing of said jaws positively upon the tape, due to the spring 308. The pivoted latch 251 swings back, Figure 6, and allows the jaws 300 and 301, upon the further and 20 proper action of the cams 61 and rollers 102, to pass back without opening and carry the length of tape to the position shown in Figure 11, this position of the tape being that where it thereafter intercepts the 25 descending blank 261 by means hereinafter 30 fully to be described.

Properly timed with the actions just described and preceding the actual rearward conveying of the tape to the position shown 35 in Figure 11, other mechanism for cutting off the length of tape has functioned in the manner now to be described. This cutting mechanism centers around the pair of cams 290 and 291 provided on the shaft 33 and a 40 pair of shears 285 and 286. Co-operating with the pair of cams 290 and 291 are a pair of rollers 178 and 179 mounted upon two arms 297 and 298 provided with outer yoke-shaped ends 289 and 294, respectively, adapted 45 to receive the shaft 33 and be guided thereby on said shaft. The lower ends of said arms 297 and 298 are secured respectively to the outer ends of the pair of shears 285 and 286 pivoted in arm 236 secured to 50 frame member 135, of which the lower shear plate is designated by 285'. Said shears, respectively, are held normally in their open position by means of springs 274 and 275 secured at one end to said arms 297 and 298 55 and at their other ends to arms 170 by means of bolts 171, said arms 170 being supported on the bracket 125. It is evident from an inspection of Figures 6 and 8 that the cam actions are such that the farthest outward 60 actuation of the arm 297 occurs concurrently with the inward actuation of the arm 298 and that these actuations result in the upward movement of the shear 285 and the downward movement of the shear 286 to 65 close said shears and sever the length of

tape 63, as plainly indicated in Figure 8, after said length of tape has been gripped by the jaws 300 and 301 in the manner shown in Figures 10 and 14 and conveyed to the pins 78, as hereinafter described.

As furnishing definite means for providing a positive station for the length of tape in a position where it may intercept the descending blank, the means now to be described are designed. These means center 75 around a cam 288 provided on the shaft 33 and the pair of vertically reciprocable members 78, hereinafter called disappearing fingers. It is evident, from an inspection of Figures 7, 10, 11 and 16, that said fingers 80 78 are periodically brought into the position shown in Figure 7 to intercept between them such part of the length of tape 63 as is necessary to form the bail of the completed pail, at or prior to the rear movement of the 85 jaws 300 and 301 with the length of tape from the position shown in Figure 10 to the position shown in Figure 11. Referring to Figure 7, it will be noted that the cam 288 co-operates with a roller 79 mounted upon 90 the arm 80, the outer end of which is yoke-shaped to receive and be guided by the shaft 33, the other end of said arm 80 being pivoted to an arm 81 pivotally supported in the bracket 169 supported upon bar 194 95 which is attached to frame member 136, said arm 81 being normally held in a position opposite that shown in said Figure 7 by a spring 84 connected at one end with said arm 81 and at its other end to said shaft 33. 100 Connected to said arm 81 are two branch arms 81', to the outer ends of which are pivotally connected short links 82 in turn pivotally connected at their other ends to said disappearing fingers 78 adapted to be reciprocated vertically in recesses 78' provided in bar 194 and thread base 180. Said bar 194 is mounted upon frame member 136. The thread base 180 is provided to give a general guideway and platform for the length of 110 tape 63.

For the purpose of freeing the severed length of tape from the jaws 300 and 301, mechanism is provided which centers around the pair of cams 57 mounted on the shaft 22, 115 the pair of trip fingers 295 and 296 and the roller 164 mounted on the bar 28 supported by said fingers 295 and 296, Figure 6. The bent ends 299 of said fingers 295 and 296 are through the cam action brought into and 120 out of the path of the pivoted jaws 300 and 301 in such timed relation to the pivotal movement of said jaws that said bent ends 299 strike the vertical portions 307 of said jaws, thus raising the upper lip 302, as 125 clearly shown in Figure 16. This action results in the freeing of the severed end of tape from said jaws. The normal position of the trip fingers 295 and 296 is that position out 130 of the path of movement of the jaws 300 and

- 301, as shown in Figure 10, and is procured through the action of springs 123 and 124 secured at one end to the bars 28 respectively, and at their other ends to the brackets 126 by means of pins 273. Said fingers 295 and 296 are pivoted intermediately of their ends to brackets 167 supported by brackets 166, as plainly shown in Figures 10, 11 and 16.
- 10 The length of tape thus brought into the machine and transversely of the front part thereof and thus severed and carried back to the station provided by the disappearing fingers 78 and in the position shown in Figure 16 then intercepts the slot portions 263 formed in the lower edges of the glued parts 270 of the blank 261, as shown in Figure 45. As the severed length of tape 63 is thus carried downwardly by the descending blank, the ends 63' of the tape disposed rearwardly of the disappearing fingers 78, Figure 11, lie in the plane of the glued portions 270 of the blank 261, Figure 46, and are rolled against and securely sealed to said glued portions by the pair of rollers 40 mounted upon shaft 168, supported in brackets 166, Figures 3, 6, 10, 11 and 16, the backing bar 39 being provided forwardly of the blank 261 against which said rollers 40 press the blank and consequently press the ends 63' into and against the glue 270.
- The continued positive downward feeding of the blank thus provided with the severed tape length is secured by means of the pair 35 of positive feeding rollers 220 and 221 mounted upon the shafts 222 and 223, Figures 3 and 6, and between which the blank is adapted to pass, as plainly shown in said figures.
- 40 Means will now be described providing a station at which the blank provided with glue and a bail, as hereinbefore fully described, may be formed up into a box or receptacle shape. These means center 45 around the mandrel 83, the cam 85 mounted upon the shaft 282 and the support stop and register plates 176 and 177, Figures 37 and 38. As soon as the central portion 268 of the blank has been fed downwardly by the 50 positive feeding means hereinbefore described to a point indicated by the ordinal 268, Figure 1, the reciprocably movable mandrel 83 adapted to be operated forwardly and rearwardly longitudinally of the machine by means of the cam 85, as herein-after fully explained, has been moved forwardly to a position somewhat to the rear of that shown in Figure 37 where the end plate 130 of the mandrel may intersect said central 55 portion 268 of the blank and carry the blank to the position shown in Figure 37, this action resulting, by means hereinafter fully described, in a bending back of the upper and lower side portions 269 of the blank 60 along the edges 264 to the position shown in Figure 47. The blank has been stopped in its downward movement and leveled up and generally prepared for the foregoing operation by means of the pair of thin support and register plates 176 and 177 carried upon the outer ends of two arms 200 supported by a second pair of arms 201 mounted in the frame members 135 and 136. The aforementioned reciprocation of the pushout plate 130 of the mandrel 83 is effected through the medium of the cam 85 mounted upon the shaft 282 and adapted to co-operate with a roller 87 mounted upon an arm 88 which is connected at its lower end to a rocking arm 216, Figure 40, rotatably mounted upon a shaft 217 supported in brackets 218 in turn supported by the rear transverse cross member 184 of the frame. Also secured upon said shaft 217 through the medium of a block 219 is a spring 215 connected to the arm 88 and so disposed as to tend to keep said arm in its extreme rear position, as shown in Figure 36. Said arm 88 at its upper end is bent rearwardly in the form shown in Figures 3 and 36 and pivoted to its extreme upper rear end is a forwardly extending arm 89 secured at its extreme forward end to a yoke-shaped arm 86, Figure 41, which yoke portions 86 are pivotally connected by means of a pin 239 to two ears 242 formed up from a guiding plate 241 of dovetail form in cross-section, as seen in Figure 41, which plate is mounted in a slide-way 240 mounted upon the transversely centrally disposed frame-member 182. A pair of steadyng members 247 of the shape plainly shown in Figures 35 and 36 are supported upon the steel support plate 175, hereinafter more fully described, and support at their outer ends said transverse frame member 182. A channel member 243, Figures 35 and 36, is provided which is formed with a tail member 244 secured to the plate 241 by means of the screws 245. Said channel member 243 is secured to the rear head of the mandrel 83, so that it is evident from the foregoing description that the actuation of the arm 88 through the operation of the cam 85 and roller 87 will result in the longitudinal reciprocation of the mandrel 83. The positive bending of the blank along the lines 264 to cause the same to assume the shape shown in Figure 47 is effected by a pair of rollers 224, Figure 39, mounted upon pins 226 which are supported in the two arms 225 of a member formed with a spindle portion 227 and adapted to reciprocate in a member 229 secured to frame member 139. A head 230, Figure 39, is secured to the top portion of the spindle 227 exteriorly of said member 229 and disposed in a recess 231 around the spindle 227 and between said head 230 and a second head 232 disposed interiorly of member 229 is a spring 228 adapted to force the roller 224 130

resiliently against the sides 269 of the blank. The springs 228 compensate for the increasing thickness of the mandrel 83, as the latter moves outwardly. The cam 85 is so constructed as to provide a "dwell" in the forward movement of the mandrel 83, when the latter reaches substantially the position shown in Figure 37, and during this "dwell" the blank, which has been bent into the form shown in Figure 47, and during the previous partial forward movement of the mandrel, is formed up into the completed box form in which it is thereafter ejected from the machine. For thus completing the forming 10 of the box and ejecting the same from the machine, means are provided which will now be described in detail.

The first of these next operations consists in turning down the upper folds 265 of the 20 sides of the box, as shown in Figure 48. Means for accomplishing this purpose center around the cam 51 provided upon the shaft 281, the bar 91 and the pair of fingers 90. The cam 51 is a groove cam and co-operating 25 therewith is a roller 94 secured at one end of the bar 91, the latter being pivoted at 93 to frame member 139 and having secured to it the pair of fingers 90 formed with inner ends 92, adapted to fold the sides 30 265 of the blank down along the side edges of the mandrel 83. A pair of springs 250 secured, respectively, to the outer ends of said fingers 90 and to said arm 91 tend to hold said fingers in the position shown in 35 Figure 43, i. e., the position when the fingers are effecting their folding operation. Said springs 250 are free to thus dispose the fingers 90 when the bar 91 is in approximately the position shown in Figure 43. 40 However, when the operation of the cam 51 upon said arm 91 brings said arm into approximately the position shown in Figure 44, said fingers 90 are separated at their inner forward ends against the action of the 45 springs 250, by reason of the fact that a pair of cam plates 97 are adjustably supported upon the steel support plate 174 and intercept a pair of rollers 96 secured to the outer ends of the fingers 90 with the result, plainly 50 shown in Figure 44, that the inner forming ends 92 of the fingers are spread apart. As plainly shown in Figures 43 and 44, allowance is made for the different distances of the respective fingers 90 from the pivotal point 93, in order that as the bar 91 swings around said pivotal point, the forming fingers 92 may affect both sides 265 of the blank in substantially the same manner.

Means now function to turn in the bottom 60 ends 266 of the blank, as shown in Figure 49. These means center around the cam 95 mounted upon the shaft 281, the pair of fingers 98 and the bar 99 mounted in the brackets 202 and 203 secured to frame member 140. Said cam 95 co-operates with a

roller 101 carried upon the end of an arm 160 in turn secured to said bar 99. Mounted upon said bar are the fingers 98 provided with the forming ends 100 so disposed with reference to the mandrel 83 as to turn in 70 the ends 266 of the blank against the sides of said mandrel. The tendency of the bar 99, under the action of spring 260, secured to a lever 259 mounted upon bar 99 and to frame member 140, is to hold said finger ends 100 in a position free from the mandrel 83, but this tendency is periodically overcome and said fingers brought into their forming position at the proper times through the action of the cam 95 and the roller 101. 80

Means are next provided for turning up the lower parts 262 of the blank, upon the portions 270 of which the glue has been applied and to which the securing ends 63' of the bail have been sealed, as hereinbefore 85 fully described, said parts 262 being turned up against the turned in end portions 266 of the blank and the folded down side portions 265. This action will result in an article of the shape shown in Figure 50 but 90 not completely sealed until some other operations have taken place thereon, as hereinafter fully described. The turning up of the portions 262 of the blank is effected by means which are centered around the cam 95 111 mounted upon the shaft 280, the pair of fingers 106 and the bar 107. This action is similar to that of the action of the cam 51, fingers 90 and bar 91. A roller 110 mounted upon the outer end of the bar 107 co-operates 100 with the cam 111 to effect a periodic raising of the inner end of said bar 107, carrying the forming ends of the fingers 106 into a position adjacent to the mandrel 83 where 105 said ends may turn up the blank portions 262. A pivotal connection for the bar 107 upon the frame member 140 is indicated by the ordinal 108 and the fingers 106 are normally held with their inner ends compressed by means of a spring 109 mounted upon a 110 pin 249, the two ends of which are mounted in the fingers 106, all as plainly shown in Figure 44. Also mounted upon the outer ends of said fingers are two rollers 112 115 adapted to contact with inclined plates 113 adjustably mounted upon the steel support plate 175, the arrangement being such that the downward movement of the fingers 106 and the contact of the rollers 112 with the plates 113 will result in the separation of 120 the forming ends of said fingers 106. These steel support plates 174 and 175 are provided upon the front of the machine and respectively mounted upon the frame members 139 and 140.

Before the forming ends of the fingers 106, however, have been withdrawn from their forming position, a subsequent operation, characterized as a general sealing process and a completing of the three forming 130

operations hereinbefore described, has commenced. This sealing operation will now be described in detail. The pair of clamping plates 118, Figure 38, are provided, which 5 are formed with recesses 161, Figure 38, into which recesses the forming ends of the fingers 106 are adapted to enter, this relation permitting the application of said clamping plates 118 to the sides 262, Figure 50, of the 10 blank 261 before the fingers 106 have been withdrawn from said recesses 161. This enables the forming fingers 106 to hold the members 265, 266 and 262 in a generally assembled position until the squeeze plates 118 15 bear upon the same. These squeeze plates 118 are mounted upon the pair of arms 116, Figure 33, pivotally mounted upon the transverse frame member 182 and carrying at their outer ends rollers 115 adapted to 20 co-operate with the pair of cams 114 secured to the shaft 282. Through the medium of a spring 172, secured at its ends to a pair of angle irons 173 in turn secured to the arms 116, the tendency of the latter is to lie with 25 their inner ends separated so as to hold the squeeze plates 118 out of the vicinity of the path of the mandrel 83. The cam 85 is so constructed and timed with reference to the mechanisms just described that immediately 30 upon the application of said squeeze plates 118 the mandrel 83 recommences its forward movement from the position shown in Figure 37 to the position shown in Figure 34, the cams 114 being so constructed that the 35 squeeze plates 118 are gradually separated enough to allow for the increasing thickness of the mandrel 83 from its forward face to its rear face. When the mandrel 83 has reached its extreme forward position as 40 shown in Figure 34, it immediately commences its return movement and during this movement means adapted positively to strip the formed pail from the mandrel are provided, whose detail and operation will now 45 be described.

The plate 130 is mounted upon the pin 131 intersecting the mandrel throughout its entire length and extending rearwardly thereof and formed into the upwardly extending end 50 portion 134. A head 155 is carried upon said pin 131 exteriorly of the mandrel and a second head 156 is mounted interiorly of the mandrel and through which said pin 131 is adapted to slide. A spring 132 is mounted upon said pin 131 and disposed between said heads 155 and 156. Supported upon the steel support plate 174 is a U-shaped member the ears 158 of which provide bearings 55 for a pin 157 upon which is pivoted the dog 133 adapted to contact with the upwardly extending portion 134 of the pin 131. As the mandrel 83 moves forwardly, the forward end of the same carries with it the plate 130 and consequently the pin 131 until 60 the parts assume the position shown in Fig- 65

ure 34 wherein it will be noted that the upwardly turned end 134 of said pin 131 has passed by and to the front of the end of the pivoted dog 133. As the mandrel 83 commences its return movement to the rear, it 70 will be evident that the contact of the member 134 with the pivoted dog 133 prevents the moving rearwardly of the plate 130 which results in the stripping by said plate of the completed box 271, Figure 50, from 75 the mandrel, as clearly shown in Figure 35. The dog 133 is provided with a downwardly inclined beveled side 163 which is intersected by the channel 243 so as gradually to raise the pivoted dog 133 which is fully accomplished to effect the release of the member 134 from said dog after the pail 271 has been completely stripped from the mandrel 83. Such release of said member 134 results in the immediate forward movement of the 80 pin 131, under the action of the spring 132, thus bringing the stripping plate 130 back against the forward face of the mandrel 83, as plainly shown in Figure 36.

It is apparent from the foregoing description and the accompanying drawings that our improved machine entirely automatically feeds, handles, forms up into completed boxes and ejects from the machine successively, flat blanks furnished in quantity 90 manually to the magazine forming part of the machine. It will also have been noted that the sequence of operations upon the blanks consist in first pasting them, then stringing them, and finally folding them 95 into completed receptacles.

What we claim is:

1. In machines for forming paper receptacles, the combination of a supporting frame; means adapted to convey a blank 105 from the top to the bottom thereof; means for applying glue to predetermined portions of said blank and means adapted thereafter to tape-tail the blank while in transit; means adapted appropriately to fold the 110 blank; and means for operating said aforementioned means in proper co-operative relation.

2. In machines for forming paper receptacles, the combination of a supporting 115 frame; means adapted to convey a vertically disposed blank therealong; means for applying glue to predetermined portions of said blank; means adapted thereafter to tape-bail the blank; means adapted appropriately 120 to fold the blank; and means for operating said aforementioned means in proper co-operative relation.

3. In machines for forming paper receptacles, the combination of a supporting frame; 125 means adapted to convey a vertically disposed blank from the top to the bottom thereof; means for applying glue to predetermined portions of said blank and means adapted to tape-bail the blank while in 130

- transit; means adapted appropriately to fold the blank; and means for operating said aforementioned means in proper co-operative relation.
5. 4. In machines for forming paper receptacles, the combination of a supporting frame; means adapted to convey a blank therealong; means for applying glue to predetermined portions of said blank; means automatically providing a tape-bail length in the pathway of said blank, said tape-bail thereafter intercepting the moving blank; means fixing said tape length to the blank; means adapted appropriately to fold the blank; and means for operating said aforementioned means in proper co-operative relation.
5. In machines for forming paper receptacles, the combination of a supporting frame; means adapted to convey a blank therealong; means for applying glue to predetermined portions of said blank; means automatically providing a tape-bail length in the pathway of said blank, said tape-bail thereafter intercepting the moving blank, the relative disposition having been such that the ends of said tape length are disposed adjacently to two of the glued portions of the blank; means adapted appropriately to fold the blank; and means for operating said aforementioned means in proper co-operative relation.
6. In machines for forming paper receptacles, the combination of a supporting frame; means adapted to convey a vertically disposed blank from the top to the bottom thereof; means for applying glue to one side of each of two of the blank flaps; means automatically providing a tape-bail length in the pathway of said blank, the forward edge of the descending blank thereafter being intercepted by said tape length, the relative disposition having been such that the ends of said tape length are disposed adjacently the glued sides of said blank; means adapted appropriately to fold the blank; and means for operating said aforementioned means in proper co-operative relation.
7. In machines for forming paper receptacles, a supporting frame; means adapted to convey a blank therealong; main tape-furnishing means comprising, a spool of tape suitably rotatably mounted, tape-guiding means formed in said frame; tape-conveying means and means for operating the same; and means adapted to sever a tape bail from the body of tape, in combination with means defining and providing an ultimate station for tape bails adjacent the path of the moving blank; and supplementary bail-furnishing means adapted bodily to convey tape bails to said ultimate station, and means for operating said supplementary means.
65. 8. In machines for forming paper receptacles, tape-furnishing means comprising, a spool of tape suitably rotatably mounted; a frame and tape-guiding means mounted thereon; tape-conveying jaws and means for opening and closing the same; means for reciprocating said jaws across said frame; means adapted to sever a tape-bail from the body of tape; means defining and providing an ultimate station for tape-bails; means adapted bodily to convey tape-bails to said ultimate station; and means for operating said last-mentioned means.
9. In machines for forming paper receptacles, tape-furnishing means comprising, a spool of tape suitably rotatably mounted; a frame and tape-guiding means thereon; tape-conveying jaws and means for opening and closing the same; means for reciprocating said jaws across said frame; means adapted to sever a tape-bail from the body of tape; reciprocable pins adapted to define and provide an ultimate station for tape-bails; means for reciprocating said pins; means adapted to convey tape-bails to said pins; and means for operating said last-mentioned means.
10. In machines for forming paper receptacles, tape furnishing means comprising, a spool of tape suitably rotatably mounted; a frame and tape-guiding means mounted thereon; tape-conveying jaws and means for opening and closing the same; means for reciprocating said jaws across said frame; means adapted to sever a tape-bail from the body of tape; means defining and providing an ultimate station for tape-bails; two sets of jaws adapted to be reciprocated between the path of the said tape-conveying jaws and said ultimate station; means for effecting said reciprocations; means adapted to cause said jaw sets to close upon tape-bails adjacently the respective ends thereof and in the path of said tape-conveying jaws; and means adapted to cause said jaw sets to release said tape-bails adjacently said ultimate station.
11. In machines for forming paper receptacles, means adapted to feed the blank in a vertical plane; means adapted to intersect the blank centrally to divert same into movement in a horizontal plane and to fold the blank back upon itself; and means adapted to fold the blank into a completed receptacle.
12. In machines for forming paper receptacles, means adapted to feed the blank in a vertical plane; means adapted to intersect the blank centrally to divert the same into movement in a horizontal plane and to fold the blank back upon itself; and means adapted successively to fold the upper sides, bottom edges, and lower sides of the blank into a completed receptacle.
13. In machines for forming paper receptacles, means adapted to convey the

blank; means adapted to fold the blank back upon itself, while conveyed; means adapted to hold the blank stationary, and means adapted to fold the blank, while so held, into 5 a completed receptacle.

14. In machines for forming paper receptacles, means adapted to feed the blank in one plane; means adapted to intersect the blank centrally to divert the same into a 10 transverse plane of movement and to fold the blank back upon itself; means adapted to hold the blank stationary; and means adapted to fold the blank, while so held, into a completed receptacle.

15. 15. In machines for forming paper receptacles, means adapted to feed the blank in one plane; means adapted to intersect the blank centrally to divert the same into a transverse plane of movement and to fold 20 the blank back upon itself; means adapted to hold the blank stationary; means adapted to fold the blank, while so held, into a completed receptacle; means then adapted to renew the movement of the receptacle in such 25 transverse plane of movement; and means

adapted to strip the receptacle from the machine while so moving.

16. In machines for forming paper receptacles, of folding means comprising, a mandrel; means adapted to cause the latter 30 to move intersect the blank centrally to bend the same back upon itself; means adapted to hold the blank stationary; fingers adapted to fold the blank, while so held, about said mandrel; and means for operating 35 said fingers.

17. In machines for forming paper receptacles, folding means comprising, a mandrel; means adapted to cause the latter to move and intersect the blank centrally to 40 bend the same back upon itself; means adapted to hold the blank stationary; three sets of fingers adapted to fold the upper sides, bottom edges, and lower sides, respectively, of said blank, while so held, about 45 said mandrel; and means for operating said fingers.

Signed by us, this 2nd day of July, 1918.

CLARENCE J. BROWN.

CLAUDE F. BROWN.
